PICKER MOTION FOR LOOMS.

Louis C. Muscatelli, Altoona, Pa.

Application April 17, 1940, Serial No. 330,220

14 Claims. (Cl. 139—225)

The present invention relates to improvements in picker motions for looms and more particularly refers to a motion for stepping-up the action of the picker shaft to increase the sweep or arc of movement of the picker stick and picker on shuttle changes in automatic looms to compensate for the space interval between the shuttle and the picker incident to the transfer of shuttles.

Heretofore in automatic looms, on the magazine side, whenever an empty shuttle is replaced by a new full shuttle it is found that such new shuttle does not in practice take up the identical position vacated by the old shuttle with respect to the picker. In practice shuttles in their movement into the boxes encounter the pickers in an advanced position and move such pickers to the initial or operative position, and in so doing the leading end of the shuttle which encounters the picker comes to rest in contact with such picker and this substantial condition is necessary for good loom operation.

In such contacting position the full force of the picker and the full sweep of the picker and its stick are felt in the shuttle to the end that the shuttle is thrown across the race to the opposite box with only such a minimum of force and length of picker travel as will accomplish the essential loom functions of causing the shuttle to arrive in the opposite box in timed relation to the other functions of the loom to the end that the loom will not be automatically stopped. In other words according to best loom practice what is known as a "soft" pick is desirable. By "soft" pick is meant a minimum of force applied by the picker and its stick to the shuttle sufficient merely to carry the shuttle through the shed and to the opposite box so that it will arrive in such box in ample time to forestall the stopping or "banging off" of the loom.

While this ideal condition is practicable at the box side of automatic looms, on the magazine side it has been necessary to adjust the picker nose closer to its operating cam or to make other adjustments in order to get a longer movement of the picker to compensate for the interval of distance between a fresh shuttle and the picker. Although this increased throw of the picker is only needed for one pick, that is on that pick occurring immediately after shuttle change, the construction of automatic looms has been such that this increased sweep of the picker and picker stick occurs throughout the entire operation of the loom.

In other words the picker nose is set permanently up closer to its operating cam or the pick-

ing motion adjusted otherwise on the magazine side of the automatic loom and consequently the picker and the picker stick at that side of the loom are required to undergo this increased sweep or length of travel. We therefore have at one side of an automatic loom a "soft" picking action, which is the desirable action and the only action that is necessary except on that one pick incident to shuttle change at the magazine side; nevertheless at such magazine side we have on every pick an undesirable undue length of picker stroke which has become known in the industry as "excessive" pick.

The "excessive" pick on the magazine side results in the following disadvantages: the breaking of picking cams, picking balls, picking shafts, pick arms, lug connectors, picker sticks, pickers, excessive wear on shuttles, imperfections in cloth, loom stoppage, increased filling waste due to bobbins bursting, indirect effect of shuttles flying out of looms due to excessive pick, etc.

The objects and purposes of the invention are to eliminate these disadvantages and to enable the use at the magazine side of the same "soft" pick as used at the box side, except only on that pick occurring at shuttle change, such shuttle change pick being increased from the "soft" to the "excessive" pick.

For convenience in illustration and explanation only one embodiment of the invention is disclosed herein in connection with Crompton-Knowles automatic loom.

With the foregoing and other objects in view the invention will be hereinafter more fully described and particularly pointed out in the subjoined claims.

In the drawings in which like reference characters refer to like parts throughout the several views,

Figure 1 is a rear elevation, with parts broken away and parts shown in section, of an automatic magazine loom equipped with an attachment constructed in accordance with the present invention.

Figure 2 is a horizontal section taken on an enlarged scale on the line 2—2 in Figure 1.

Figure 3 is a fragmentary side view taken from the left side in Figure 2.

Figure 4 is a similar view taken from the right side in Figure 2.

Figure 5 is a perspective view of the picker nose.

Figure 6 is a fragmentary side view taken from the right side of the loom as shown in Figure 1.

Figure 7 is a vertical section taken on the line 1—7 in Figure 6.

Figure 8 is a fragmentary top plan view similar to Figure 2 showing the slide and collar in the engaged position.

Figure 9 is a fragmentary top plan view with parts shown in section showing a modification, and

Figure 10 is another fragmentary side view with parts broken away showing a further modification.

Referring more particularly to the drawings, 10 designates the frame of a Crompton-Knowles or other conventional type automatic loom. Journaled in this frame is the customary bottom shaft 11 which carries the cam 12 for rocking the picker shaft 13.

The picker shaft is customarily square in cross section and carries the picking arm 14 which operates the picker stick 15 and the picker in a well known manner.

The cam 12 operates in conjunction with a picker nose 16 carried by the picker shaft 13 and ordinarily adjustable axially along the picker shaft 13 toward and from the center line of the bottom shaft 11 and operating cam 12. The adjustment is secured by the use of set screws 17. In this way by adjusting the picker nose 16 further away from such center line the angular 25 rocking of the picker shaft 13 may be reduced causing a "soft" pick at the box side of the loom. At the magazine side of the loom it is the practice to adjust the picker nose 16 closer to the picking cam 12 to secure the "excessive" pick heretofore referred to.

The standard automatic loom also involves a box motion arm 18 at the magazine side of the loom moved incident to the changing of the shuttle. The standard loom also contains the bearings 19 for the picker shaft 13, the picker shaft having round trunnions 20 which freely turn in the bearings 19.

In accordance with the invention one or both ends of the enlarged square portion of the picker shaft 13 are reduced or cut-away to admit a 45 collar 21 and one end of a slide 22 and to admit of such end play of the trunnions 20 in bearings 19 as to enable the picker shaft 13 and the picker nose 16 carried thereby to be moved axially as a unit for the purpose of advancing the picker nose 16 closer to its operating cam 12 at that period desirable for making the "excessive" pick, namely at shuttle change. A coil spring 23 is arranged to automatically shift the picker shaft 13 in one direction, namely in that direction to carry the picker nose 16 away from its operating cam 12. Such coil spring is shown as connected between a spring anchor arm 24 which is bolted or otherwise secured to an appropriate part of the framework of the loom and a set collar 25 which is made fast on the square portion of the picker shaft 13.

The collar 21 is removably fitted over one trunnion 20 and moved up against the adjacent end of the picker shaft 13 where it is secured as by a set screw 26. Such collar carries a beveled or tapered face 27 positioned to mate with a similar beveled or tapered face 28 on the slide 22. The slide 22 comprises thick and thin portions at opposite sides of its beveled face 28. When the thin portion is opposite the collar 21 coil spring 23 moves the assembly to a position where picker nose 16 is remote from its operating cam 12 resulting in a "soft" pick. When slide 22 is advanced with its bevel face 28 riding over the simi-

lar face of its complementary collar 21 the thick portion of slide 22 is introduced between collar 21 and the adjacent end of the bearing 19 causing a shift endwise of the picker shaft assembly resulting in the movement of picker nose 16 closer to its operating cam 12, resulting in an "excessive" pick.

The slide is formed with a slot 29 elongated in a horizontal direction and received over the trunnion 20 whereby the trunnion 20 becomes a support and a guide for this end of the slide 22. The slide has at its other end a bar 30 slidable through a slot 31 in a slide hanger 32, which hanger has an elongated slot 33 to adjustably receive a bolt 34 carried by a lug 35 of a supporting bracket 36. The bracket is affixed to an appropriate part of the framework of the loom. The slot 33 affords a vertical and a limited swinging adjustment of the hanger 32 to cause it to take up a proper position with respect to the bar 30 of the slide which is movably supported thereby.

The slide 22 carries an upstanding slide boss 37 perforated to receive slidably therethrough a pull rod 38 which is connected to operating parts cooperating with the box motion arm 18 for shifting the slide 22 to cause its thicker portion to wedge against the collar 21.

The slide 22 also has an opening or other connection 39 to receive a release or pull-back rod 40 connected to a train of mechanism for operating upon the slide to restore it to its initial normal position where the thin part thereof is against collar 21 and the picker shaft assembly is in the "soft" picking position.

The pull rod 38 extends slidably through the boss 37 and carries a set collar 41 positioned to encounter the boss in the forward movement of the pull rod 38.

The pull rod is pivoted in the lower arm 42 of a bell crank fulcrumed at 43 in a bracket 44 carried by the framework of the loom. The upper arm 45 of the bell crank is formed with a socket 46 in position to receive the free ball end of a finger 48, which finger is carried by a shaft 49 extending out beyond the magazine side of the loom and mounted in bearings 50 carried by a bracket 51 bolted or otherwise secured to the framework of the loom. Also secured upon the shaft 49 is an arm 52 extending toward the front of the loom and connected by a link 53 with the end of the box motion arm 18 whereby lowering and raising of the box motion arm 18 will cause the shaft 49 to rotate back and forth in accompaniment. Set collars 54 on shaft 49 prevent the shaft from accidental endwise shift.

The release rod 40 for the slide extends across the loom and beyond the opposite side thereof where its lower end is adjustably connected in a slot 55 of the lower arm 56 of a bell crank lever fulcrumed at 57 in bracket 58; said bracket being affixed to an adjacent part of the loom frame. The perforated upper arm 59 of the bell crank is connected to an operating rod 60, such rod fitting in a selected perforation of the upper arm 59 for purpose of adjusting the throw of movement of the device. The upper end of rod 60 is slidably received through an aperture 61 in a lever 62. The lever 62 is fulcrumed at 63 on bracket 64 adjustably bolted or otherwise secured to an appropriate part of the loom frame.

The free end of the lever 62 rests upon a cam 65 fixed upon the bottom shaft 11.

In operation the normal position of the slide 22 is in the retired position where the thin portion thereof lies between the collar 21 and the

adjacent end of bearing 19. In this position coil spring 23 has shifted the picker shaft assembly to the "soft" picking position. The loom will continue to run in this position until it is desired to change a shuttle. At this point the loom must be set in such a manner as to deliver "excessive" pick to compensate for the loss of picking that occurs when the new shuttle replenishes the empty. As the new shuttle receives its inward motion box motion arm 18 receives a downward motion taking with it arm 52 which rocks the shaft 49 depressing finger 48 and shifting the bell crank 42, 45 pulling on the rod 38. Due to the engagement of the collar on pull rod 38 with the slide boss 37, the slide 22 is pulled toward that side of the frame in which the shaft 49 is journaled causing the thickened portion of the slide 22 to enter between collar 21 and bearing 19 which results in the endwise shift of the picker shaft assembly.

Immediately the box motion arm 18 returns to its normal position causing a reversal of movement in the train of parts back to the pull rod 38, the pull rod sliding through the eye of the slide boss 37 without affecting the slide 22 which must be left in this shifted position until the "excessive" pick has taken place. The raising of the finger 48 in socket 46 will lift the upper arm 45 of the bell crank lever by engagement of the finger with a cotter pin 67 or other suitable connecting member.

When the slide 22 was moved into the "excessive" pick position it pulled upon rod 40 thus rocking the bell crank 56, 59 and drawing down rod 60 until set collar 66 carried by the rod 60 engaged the upper side of the cam lever 62. The cam 65 rotating around with bottom shaft 11 is timed to lift lever 62 immediately after the "excessive" pick has been delivered. The lifting of this cam lever 62 will through the set collar 66 operate to shift bell crank 56, 59 in an opposite direction, thus exerting a pull upon the release rod 40 with sufficient throw to restore the slide 22 to the "soft" pick position where the thin part thereof is presented to the collar 21, thus enabling the coil spring 23 to restore the picker shift assembly to the "soft" pick position. In this position the loom is allowed to run until another shuttle change occurs.

When the release rod 40 moves the slide 22 back to its inoperative or "soft" pick position it shifts slide boss 37 into engagement with the collar on the push rod 38 so that these parts are engaged for subsequent actuation.

The set collar 66 in the normal position stands in spaced relation above the cam lever 62 so that the lifting of the cam lever 62 by the cam 65 will have no effect on the rod 60 during the normal running of the loom. The set collar 66 is only drawn down when the slide 22 is engaged.

Figure 2 shows the disengaged position of the slide 22 and Figure 8 shows the engaged position thereof. The disengaged position is when the thin portion of the slide is between collar 21 and bearing 19. The engaged position or advance position of the slide occurs when the thick portion of the slide-wedge is entered between collar 21 and the adjacent bearing 19.

In Figure 9 there is shown a modification in which the picker nose 16^a has its set screws 17 removed so that it is directly slidable in an axial direction relatively along the square portion of the picker shaft 13. In this instance the collar 21 is dispensed with and the bevel shoulder 28^a of slide 22 is received against a comple-

mental bevel shoulder 27^a formed directly upon the picker nose 16^a so that shifting of slide 22 to the engaged position will cause the picker nose 16^a to be shifted along picker shaft 13 into a closer position with respect to its actuating cam.

In this instance it is not necessary to cut down the square portion of the picker shaft to admit the collar and the slotted end of the slide about the rounded trunnion of the picker shaft but all that is necessary is to cut a slightly wider slot 29 in the slide 22 to allow for the square portion of the picker shaft 13 to turn therein. This will of course tend to oscillate slide 22 slightly in a vertical plane but the loose fit of the slide bar 30 in its hanger 32 will allow for any such inequalities of movement. A coil spring 23^a keeps the picker nose 16^a up against the slide and in a remote or "soft" picking position with respect to its actuating cam. The coil spring 23^a reacts against set collar 25.

In carrying out the invention it is only necessary that the picker nose 16^a, which is referred to broadly in the claims as the control member because its position with respect to the actuating cam regulates the amount of pick, receive the automatic movement toward its actuating cam 12. In other words it is not necessary that the picker shaft itself be moved. However it is convenient to utilize the picker shaft 13 as a carrier for the picker nose 16 and to move the entire shaft assembly in an endwise or axial direction because in so doing the picker nose may still have the benefit of its set screw adjustment along the picker shaft. It therefore may be set in any picking position desired when the picker shaft or some other carrier member on which the picker nose can be longitudinally adjusted is utilized.

The operating cam 12 and the picker nose form a couple in the picking motion of an automatic magazine loom. It will be understood however that the invention is not limited to the Crompton-Knowles in which, for convenience of illustration, the invention has been described, but the invention is applicable to any automatic magazine loom having any type of picker motion in which there is an actuating member, such as cam 12, and a control member, such as picker nose 16 or 16^a which by its adjustment toward and from its cam or actuated member controls the degree of the pick.

With regard to Figure 10 the advantages of securing manual adjustment of the picker nose 16^b along the square portion of the picker shaft 13 are secured without requiring any modification in construction of the picker shaft and without requiring that the picker shaft be moved axially or endwise, by employing a sleeve 68 slidably mounted upon the square portion of the picker shaft 13 as the endwise moving carrier for the picker nose 16^b on which the picker nose may be manually adjusted as by its set screw 17^b to any position relatively to the actuating cam 12. In this instance the slide 22 is shown as operating against the end of the sleeve 68 although such slide may operate against the end of the picker nose as shown in Figure 9. A spring 23^b may be employed to bias the sleeve 68 to a position in which the picker nose 16^b is in its most remote position from the actuating cam 12. This is the position of "soft" pick to which the operator has adjusted the picker nose 16^b. The slide moves the sleeve 68 and picker nose over to the stepped up or "excessive" pick position.

In Figures 9 and 10, 70 represents a stop or abutment against which the coil spring moves the nose and slide. Such stop 70 also assists as a guide for the slide.

It is obvious that various changes and modifications may be made in the details of construction and design of the above specifically described embodiment of this invention without departing from the spirit thereof, such changes and modifications being restricted only by the scope of the following claims.

What is claimed is:

1. In apparatus for increasing the picking action on shuttle-change in an automatic magazine loom, an actuating couple in the picker motion of the loom comprising a movable control member and its actuating member, an automatic mechanism for the movable control member so constructed and arranged that it is actuated to move the control member with respect to its actuating member by a change of shuttles to vary the picking action during such change of shuttles.

2. In an automatic magazine loom, the combination of an actuating member for the picker motion, a control member movable relatively to the actuating member, and means operated by the replenishing mechanism of the loom to cause the said control member to approach more closely to the actuating member during shuttle-change in the magazine, the whole operating for the purpose of securing normally on the magazine side of the loom a "soft" pick and an "excessive" pick on shuttle-change.

3. In an automatic magazine loom, an actuating member for the picker motion, a control member cooperatively mounted relatively to said actuating member, a movable carrier for said control member biased to a position where the control member is in "soft" picking relation to the actuating member, and operating means for the carrier adapted to cause the said carrier to move the control member closer to the actuating member to vary the picking action.

4. In an automatic magazine loom, an axially slidable picker shaft, a picker nose adjustably and fixedly mounted on said shaft, an actuating member in operative relation to said picker nose, wedge means for sliding said shaft to cause the nose to approach the center line of the actuating member, means for withdrawing said wedge means to initial disengaged position, and means for shifting said shaft and nose away from the center line of the actuating member.

5. In an automatic magazine loom, an axially shiftable picker shaft, a picker nose adjustably and fixedly mounted on said shaft, an actuating member cooperatively positioned relatively to said nose, means for yieldably shifting said shaft in one direction, a slide member for shifting the shaft in the opposite direction, a box motion arm, a connection between said box motion arm and said slide member for moving the slide member into engaged position with said shaft and thereafter immediately moving back to initial position without entraining said slide therewith, and means for drawing the slide back to disengaged position after the "excessive" shuttle-change pick.

6. In an automatic magazine loom, an axially shiftable picker shaft, a picker nose carried by said shaft, an actuating member cooperating with said nose, yieldable means for shifting said shaft in one direction, a slide for moving said shaft in the opposite direction, a rod slidably

engaged with said slide and having an abutment member adjustably mounted thereon for engaging said slide to move said slide to the engaged position and to permit the rod to be moved back to initial position without effecting disengagement of said slide, a movable shuttle-change member, connections between said shuttle-change member and said rod for effecting back and forth movement of said rod, and means for moving said slide to disengaged position timed to follow after the pick occurring after shuttle-change.

7. In an automatic magazine loom, an actuating member for the picker motion, a picker nose cooperating with said actuating member, an axially shiftable picker shaft carrying said nose, a slide for moving said picker shaft in one direction, yieldable means for restoring said shaft in the other direction, a pull rod slidably connected with said slide, an adjustable abutment member on said rod for engaging said slide, a bell crank lever having one arm connected to said rod and another arm having a socket, a movable finger having a ball disengageably fitted in said socket, a rock shaft carrying said finger and mounted on the loom, a movable shuttle-change member operatively connected to rock said rock shaft, and means for drawing the slide back to disengaged initial position.

8. In an automatic magazine loom, an adjustable picker motion, means for adjusting said picker motion to increase the pick at shuttle-change, said means comprising a slidable member, and means for restoring the slidable member to initial disengaged position comprising an operating member driven continuously by said loom, connections between said operating member and said slide, and a lost motion element in said connections moved by the slide into tight connection when the slide is engaged.

9. In an automatic magazine loom, an adjustable picker motion, means for adjusting said picker motion to give an "excessive" pick on shuttle-change comprising a slide, a movable shuttle-change member, and connections between said member and said slide for moving the slide into engaged position, and means for moving said slide back to disengaged position comprising a rod, a bell crank lever having one arm adjustably connected to said rod, an operating rod connected to the other arm of said bell crank, a lever adjustably fulcrumed on the loom frame, a bottom shaft for the loom, a cam fixed to said bottom shaft and engaging said lever, said lever having an opening through which said operating rod extends, and a set collar on said adjusting rod forming a lost motion connection and normally standing away from said lever but moved by the slide into engagement with the lever when the slide is shifted to engaged position.

10. In an automatic magazine loom, an actuating cam for the picker motion, a picker nose shiftable with respect to said cam having a wedge face, a slide having a cooperating wedge face adapted to shift said nose toward its cam when the slide is moved to engaged position, yieldable means for urging the nose against the slide, a movable shuttle-change member, connections between said shuttle-change member and the slide for advancing the slide to engaged position, and automatic means driven by the loom for drawing the slide back to the initial disengaged position.

11. The combination with an automatic maga-

zine loom having a shuttle changing mechanism and a picking cam, of an adjustable picker nose adapted to engage said cam to produce a normal picking action, and means operated by said shuttle changing mechanism to adjust the relative positions of said picker nose and cam to produce an abnormal picking action on the pick immediately following the change of shuttles.

12. The combination with the picking means of an automatic replenishing loom and an adjustable picker nose, of automatic replenishing mechanism, connections between said replenishing mechanism and said picker nose for bringing said picker nose into appropriate relation with the picking means on operation of the replenishing mechanism to effect an increase in the picking action on the first pick after replenishment.

13. The combination with an actuating member of a picker motion of an automatic replenishing loom and a control member adjustable towards and from the actuating member to reg-

ulate the amount of pick, of automatic replenishing mechanism, connections between said automatic replenishing mechanism and said control member, said automatic replenishing mechanism shifting said control member with respect to said actuating member on operation of the automatic replenishing mechanism to effect an increase in the picking action on the first pick following replenishment.

14. In an automatic replenishing loom, the combination of an automatic replenishing mechanism, a picker motion comprising an actuating member and a picker nose, means operating said picker motion to produce a normal picking action, and means operated by said replenishing mechanism after the first pick only following replenishment to vary the relative position of said actuating member and picker nose, the whole operating for the purpose of increasing the picking action of the first pick only following replenishment.

LOUIS C. MUSCATELLI.
